UNITED STATES PATENT OFFICE.

EUGÈNE SCHNEIDER, OF LE CREUZOT, FRANCE.

MEANS OF ASSEMBLING THE ELEMENTS OF A SECTIONAL GUN-BARREL.

1,234,575.

Specification of Letters Patent. Patented July 24, 1917.

Application filed February 11, 1916. Serial No. 77,714.

To all whom it may concern:

Be it known that I, EUGÈNE SCHNEIDER, a citizen of the Republic of France, residing at Le Creuzot, France, have invented a new and useful Improvement in or Relating to Means of Assembling the Elements of Sectional Gun-Barrels, which is fully set forth in the following specification.

This invention has for its object to provide an improved and extremely simple means of assembling and disassembling the elements of a sectional gun barrel comprising a gun tube and a breech piece, with and from each other, and a third element, namely, a slide that carries the gun barrel.

The improved means allows by a simple angular displacement of one of the elements, of effecting the simultaneous assemblage of the two elements constituting the gun barrel with each other and with the third element, viz., the slide. The disassemblage of the two elements of the gun barrel from each other and from the third element, viz., the slide, is effected by merely reversing the direction of the assembling angular movement.

The manner in which the invention is to be performed will now be more particularly described with reference to the accompanying illustrative drawings in which:—

Figures 1 and 1^a are a longitudinal section partly in side elevation of a constructional example showing the elements of the gun barrel assembled with each other and with the third element, viz., the slide.

Figs. 2 and 2^a are a side elevation partly in longitudinal section of one of the elements (the gun tube) of the gun barrel separate from the other element (the breech piece) of the gun barrel, and without the slide.

Fig. 3 is a side elevation partly in vertical section of the breech piece shown separately, with the internal screw threaded sleeve and the peculiar assembling means of the invention.

Figs. 4 and 4^a are a side elevation of the slide, part of the front side wall being broken away to show the internal parts.

Fig. 5 is a cross section on the line V—V of Fig. 1.

Fig. 6 is a cross section on the line VI—VI of Fig. 4^a.

Fig. 7 is a rear end elevation of the slide, the elements of the gun barrel being shown in section in the upper part of the figure.

Fig. 8 is a detail drawn to a larger scale, in section on the line VIII—VIII of Fig. 3.

As shown, the gun barrel is composed of two main elements, namely, the gun tube A—A¹ shown separately in Figs. 2 and 2^a, and the breech piece B—B¹ (Fig. 3). The two parts A and A¹ are connected permanently and they constitute together the gun tube. Similarly the two parts B and B¹ are connected permanently and constitute the breech piece which according to the invention does not become separated from the assembling screw sleeve C (Fig. 3).

D is the slide that constitutes the third element to be assembled. For transport the three elements, namely, the gun tube, the breech piece with the assembling screw sleeve, and the slide, have to be disassembled from one another.

According to the invention the assembling of these three main elements is effected by simply sliding these elements into position for being assembled, and then simply turning the assembling screw sleeve which is connected permanently to the breech piece.

For the purpose of bringing the elements into position for being assembled, the slide D is provided with two rolling tracks d—d on which rollers a are arranged to roll, that are carried by brackets a¹ projecting from a hoop a² on the tube. This hoop a² has projecting from its underside a tenon a³ which engages in a similarly shaped recess d¹ in the slide D. Bearing surfaces d² are provided on the slide for supporting the fore-part A¹ of the gun tube sleeve A¹. A spring bolt E provided on the slide is adapted to lock the gun tube A—A¹ in the requisite position for assemblage by engaging in a socket a⁴ in the tenon a³.

Two pairs of rollers b—b, b¹—b¹ arranged to roll on the same rolling tracks d—d on the slide, are carried respectively by the parts B and B¹ of the breech piece. The rollers b are mounted on journals formed at the ends of arms b² (Fig. 3).

For the purpose of assembling the three elements A—A¹, B—B¹ and D, these elements are formed in the usual manner each with longitudinal rows of teeth arranged in the form of toothed sectors on the cylindrical surfaces of the elements, these rows of teeth being separated from one another by plain rows of the same width. Thus the gun tube sleeve A¹ is formed with longitudinal

rows of external teeth a^5 ; the assembling sleeve C forming part of the breech piece B—B¹ is formed with longitudinal rows of internal teeth c^2 and with longitudinal rows 5 of external teeth c ; and the slide D is formed with longitudinal rows of internal teeth d^3 .

In the example shown, the slide D has four longitudinal rows of inwardly projecting teeth d^3 , these rows being separated from 10 one another by plain intermediate longitudinal portions d^4 of the same width.

To the spaces d^4 between the teeth of the rows d^3 there correspond external teeth c formed on the assembling screw sleeve C which, as already stated, is carried permanently by the breech piece B—B¹ on which it screws by means of a rearward screw thread C¹. The rows of teeth c of this sleeve are arranged so as to alternate with 15 plain intermediate longitudinal portions c^5 of the same width (Fig. 3).

The assembling sleeve C is formed on its inner surface with a number of longitudinal rows of teeth c^2 alternating with plain intermediate longitudinal portions c^3 of the same width (Fig. 3). The teeth c^2 are designed to engage teeth a^5 arranged in longitudinal rows on the tube A¹ which are 20 likewise separated from one another by plain intermediate longitudinal portions a^6 of the same width.

The mechanism for effecting simultaneous engagement between the element C—B—B¹, and the element A—A¹ on the one hand, and 25 between the entity C—B—B¹—A—A¹ and the slide D on the other hand, comprises simply a transverse rack F which is composed of helical teeth fixed or formed on the assembling screw sleeve C, and is adapted to be turned through an angle corresponding to the width of the toothed and plain longitudinal rows, by means of a worm G journaled in a bearing H formed or mounted on the breech piece B—B¹. 30 This angular rotation which is executed in one or the other direction for the purpose of effecting engagement or disengagement, is limited in both directions by a stop A² (Fig. 1^a) which projects from the tube A¹, abutting against the sides of a recess C² formed in the forward face of the assembling sleeve C.

Normally the rack F remains engaged in a position corresponding to the position 35 which is to be occupied by the common assembling sleeve C, that is to say completely screwed up, or completely unscrewed. For this purpose the operating worm G is formed with a recess g of square section adapted to receive the square part i of the spindle or crank shaft I which is provided with the operating lever K (Fig. 8). A spring g¹ has a constant tendency to keep the spindle I in the position shown 40 in Fig. 8, in which position a key I¹ carried

by the said spindle engages a part H¹ of the recess in the bracket H which is formed with a stop h¹. The spindle I has thus only a very limited possibility of movement.

When it is desired to rotate the spindle I 45 for the purpose of screwing up or unscrewing the sleeve C, the spindle must be pushed forward more into the screw G by compressing the spring g¹ until the key I¹ becomes engaged in the annular recess H². 50

By rolling the tube A—A¹ into position on the slide D, the tenon a³ becomes automatically caught by the spring bolt E. Then the breech piece B—B¹ with the assembling sleeve C carried by it, which is 55 locked in the unscrewed position, is rolled into position, the breech end B¹ engaging by means of an annular shoulder b³ (Fig. 1^a) in an annular groove in the tube end face. At the same time external nubs a⁷ 60 on the tube A engage in corresponding internal recesses b⁴ in the breech piece B. The internal teeth c² of the sleeve C are at this moment engaged in the plain external longitudinal portions of the tube A¹ while 65 the external teeth c of the said sleeve are engaged in the plain longitudinal portions of the slide D.

To assemble the elements, it is sufficient to 70 push the spindle I right in by means of its operating lever, and then to rotate it until a resistance is felt due to the tenon A² butting against the side of the recess C². The spindle I on being let go, will return into the position shown in Fig. 8. 75

The spindle I has merely to be rotated in the reverse direction in order to disassemble 80 the elements.

The sleeve C grips the breech piece B and the tube A owing to the difference between 85 the pitches of the screw threads a⁵ on the tube A and the screw threads C¹ of the sleeve C. These parts are jointed together by means of a packing ring J fixed on the breech piece B, the forward face of the said 90 ring being made to fit against the corresponding face of the tube A¹. The jointing is adjusted so that those surfaces of the screw threads c² and a⁵ that are at right angles to the axis of the gun barrel on the 95 one hand, and those of the screw threads C¹ of the assembling sleeve C and the breech piece B on the other hand, shall be in contact with one another. It is necessary that 100 all "play" shall be avoided, in order that when the gun is fired no violent impact shall take place between the said surfaces by the recoil of the elements B and C due to the action of the powder gases.

The packing ring J which effects the de- 105 sired jointing can be easily adjusted and renewed when necessary if the screw threads C² and C¹ of the sleeve C shall have become at all loose on the screw threads of the parts A¹ and B. 110

Having now described my invention what I claim as new and desire to secure by Letters Patent is:—

1. In combination, a breech piece and gun tube separable therefrom, a slide for supporting said breech piece and tube, an assembling sleeve having threaded engagement with said breech piece and provided with external and internal interrupted threads, said tube and slide each being provided with interrupted threads permitting bayonet engagement of the sleeve, tube and slide, and sleeve-operating means mounted on the sleeve and breech piece adapted to rotate the sleeve into and out of assembling position.
2. In combination, a breech piece and gun tube separable therefrom, a slide for supporting said breech piece and tube, an assembling sleeve having threaded engagement with said breech piece and provided with external and internal interrupted threads, said tube and slide each being provided with interrupted threads permitting bayonet engagement of the sleeve, tube and slide, and sleeve-operating means carried by the sleeve and breech piece comprising a rack, a worm gear engaging the rack, and a crank shaft yieldingly held in locked position against rotation and designed to rotate said gear.
3. In combination, a breech piece and gun tube separable therefrom, a slide for supporting said breech piece and tube, an assembling sleeve having threaded engagement with said breech piece and provided with external and internal interrupted threads, said tube and slide each being provided with interrupted threads permitting bayonet engagement of the sleeve, tube and slide, and sleeve-operating means carried by the sleeve and breech piece comprising a rack, a worm gear engaging the rack, a crank shaft yieldingly held in locked position against rotation and designed to rotate said gear.
4. In combination, a breech piece and gun tube separable therefrom, a slide for supporting said breech piece and tube, an assembling sleeve having threaded engagement with said breech piece and provided with external and internal interrupted threads, said tube and slide each being provided with interrupted threads permitting bayonet engagement of the sleeve, tube and slide, and sleeve-operating means carried by the sleeve and breech piece comprising a rack, a worm gear engaging the rack, a crank shaft yieldingly held in locked position against rotation and designed to rotate said gear.

tion against rotation and designed to rotate said gear, and spring-pressed means in the path of the gun tube for locking the tube against longitudinal movement in one direction.

4. In combination, a breech piece and gun tube separable therefrom, a slide for supporting said breech piece and tube, an assembling sleeve having threaded engagement with said breech piece and provided with external and internal interrupted threads, said tube and slide each being provided with interrupted threads permitting bayonet engagement of the sleeve, tube and slide, and sleeve-operating means mounted on the sleeve and breech piece adapted to rotate the sleeve into and out of assembling position, and spring-pressed means in the path of the gun tube for locking the tube against longitudinal movement in one direction.

5. In combination, a breech piece, a gun tube, a removable jointing ring intermediate the tube and breech, a slide supporting said tube and breech, an assembling sleeve having threaded engagement with said breech piece and provided with external and internal interrupted threads, said tube and slide each being provided with interrupted threads permitting bayonet engagement of the sleeve, tube and slide, the threads on the tube differing in pitch from those on the breech, and means mounted on the sleeve and breech adapted to rotate the sleeve on said tube and breech to clamp said jointing ring between the assembled tube and breech.

In testimony whereof I have signed this specification in the presence of two subscribing witnesses.

EUGÈNE SCHNEIDER.
